DESIGN.

F. A. RUGEN.

CARPET.

No. 17,206.

Patented Mar. 22, 1887.

UNITED STATES PATENT OFFICE.

FREDERICK A. RUGEN, OF BROOKLYN, NEW YORK, ASSIGNOR TO THE
HARTFORD CARPET COMPANY, OF HARTFORD, CONNECTICUT.

DESIGN FOR A CARPET.

SPECIFICATION forming part of Design No. 17,206, dated March 22, 1887.

Application filed February 18, 1887. Serial No. 238,122. Term of patent 3½ years.

To all whom it may concern:

Be it known that I, FREDERICK A. RUGEN, a citizen of the United States, residing in Brooklyn, county of Kings, State of New York, 5 have invented a new and original Design for Carpets, of which the following is a specification, reference being had to the accompanying photograph, which forms a part of the same.

The invention relates to a design to be worked 10 into or upon surfaces, such as carpets or similar fabrics; and it consists in the novel configuration and grouping of figures herein specifically shown and claimed.

The accompanying photograph is a face view 15 of a carpet showing my new design.

The main features of the design are the large scroll-like figures with conventionalized heads.

As shown, the figures are connected on inconspicuous stems, and are of various shapes. Some of the scroll-shaped figures have a checkered or blocked appearance produced by the intersection of two systems of parallel lines. 20 These checkered scroll-like figures are scattered irregularly among larger flower and leaf forms or clusters.

What I claim as new, and desire to secure 25 by Letters Patent, is—

The design for carpets, consisting of the design, substantially as shown and described.

FREDERICK A. RUGEN.
